UNITED STATES PATENT OFFICE.

GEORGE C. PLUMMER, OF PHILADELPHIA, PENNSYLVANIA.

CONVEYER-BELT.

No. 821,121.

Specification of Letters Patent.

Patented May 22, 1906.

Application filed April 18, 1905. Serial No. 256,239.

To all whom it may concern:

Be it known that I, GEORGE C. PLUMMER, a citizen of the United States, residing at Philadelphia, county of Philadelphia, and State of Pennsylvania, have invented a new and useful Improvement in Conveyer-Belts, of which the following is a full, clear, and exact description, reference being had to the accompanying drawings, which form a part of this specification.

My invention relates to conveyer-belts for use on troughing-rollers.

The object of the invention is to minimize the destructive effects arising from the bending of the belt along longitudinal lines at the angles of divergence between the flat and turn-up portions of the belt and secure flexibility of the belt along these lines without at the same time resorting to any expedient that will thin or weaken these portions of the belt or render the belt as a whole less firm and wear-resisting than is practically necessary.

To this end my invention consists of a belt made of two or more comparatively thin sheets of belting material secured together along their longitudinal central portions, but left independent of each other between their middle parts and their edges.

Before setting forth more specifically the construction of my improved belt it may be well to briefly describe the present general system of "troughing - belt" conveyers or "troughed - belt" conveyers and the cause and nature of the destructive wear to which their belts are exposed.

Belt conveyers in general consist, essentially, of two end pulleys around and between which an endless belt is arranged to run. That part of the belt between the upper parts of the two end pulleys may be called the "upper run" and that part between the lower parts of the pulleys the "lower run." The material to be handled is usually placed on the upper run of the belt. To cause the belt to assume a trough shape, it is customary to cause the same to travel over idler-pulley supports arranged in a trough shape. A preferred form of such idler-pulley supports consists of sets of idlers, each set composed of a central flat pulley and two turn-up or inclined pulleys. The run carrying the load is the only part of the belt that is supported on troughing-rollers, and which in consequence is troughed. To keep it from sagging unduly, the return run of the belt—that run

which is not loaded—is usually supported at intervals by flat rollers on which the belt lies flat. The end pulleys also are necessarily flat, or approximately so. The normal form, therefore, of a conveyer-belt is flat. Therefore when a conveyer-belt is troughed or bent into a curve shape distortion from its normal transverse section takes place. Being bent or curved, the surface and parts adjacent thereto at the inside of the curve tend to become compressed, while the surface and parts adjacent thereto at the outside of the curve tend to become stretched. Extreme transverse bending or curvature of a belt of appreciable thickness will finally buckle the surface and adjacent parts along the inside of the curve and rupture and tear apart the surface and adjacent parts along the outside.

Belts are "troughed" in order that they may carry comparatively large loads without spilling the same, and as the angle or degree of troughing within limits increases the belt carrying capacity increases. As the degree of troughing increases so does the distortion and consequent strain of a given belt. Also as the thickness of a belt of a given material as heretofore constructed increases so also does its resistance to troughing increase.

In order to impart sufficient flexibility to the belt along the lines of bending, different expedients have been resorted to, and troughed conveyer-belts in commercial use are either made especially flexible as a whole by making them of some soft yielding material or else the essential resistive substance of the belt along the lines of bending is made thinner than elsewhere. Belts thus constructed attain the advantage of flexibility along the lines of bending at the sacrifice of durability. A belt to resist the wear of loadings of heavy and rough or abrasive material must be firm and wear-resisting throughout, so that it may present a surface that may appreciably wear away without being thereby rendered entirely useless, and to resist the blows of loading without being punctured it must have a good thickness throughout. It is obvious that a belt made throughout of soft and yielding material will not fill these requirements. It is equally evident that a belt made thin in part will be weak in that part and that the life of the belt as a whole cannot exceed the life of its weakest part. In my belt I attain the advantage of capacity for readily flexing and bending and at the

same time secure the advantages of a belt of firm and wear-resisting qualities and of the desired thickness throughout. Its preferred construction will be understood by reference 5 to the accompanying drawings, in which—

Figure 1 is a sectional view of the belt shown supported on troughing idler-pulleys, the latter being shown in side elevation. Fig. 2 is a sectional view of a modification. Fig. 3 is a sectional view of another modification. Fig. 4 is a plan view of a short length 10 of the belt of Fig. 1.

Referring first to the construction shown in Fig. 1, *a a a* are the troughing-pulleys. *b b* are two pulleys so placed as to prevent the belt from running too far over sidewise. The belt is composed of two leaves, sheets, or sections—an upper section *c* and a lower section *d*. Between the points *e* and *f*—that is, the 15 longitudinal central portion of the belt—the two sections are secured together by means of rivets *g* and stitches *h*, extending through both sections. This portion of the belt is therefore to all intents a single or unitary 20 thick belt. Between the points *e* and *f* and the respective edges of the belt the two sections are in a sense entirely independent in that they are not secured together, while in another sense having no longitudinal movement 25 in relation to each other they form together a combination-belt, and therefore retain all the advantages of a unitary belt of the required thickness and firmness. At the same time each section is at liberty to bend 30 independently along the longitudinal lines dictated by the arrangement of the troughing-idlers.

The freedom with which the upper and lower sections of the belt can bend independently of each other is a feature of great importance. A thin piece of material bends more readily than a thick piece. Theoretically and practically to all intents each half 40 of my belt will be subjected to strains of only one-quarter of the intensity of those that the belt would be subjected to were both halves secured together, so as to bend or flex as one piece.

In Fig. 1 it will be noted that the edges of the upper half of the belt project materially beyond those of the lower half. In reality the upper half of the belt is no wider than the lower half, and the displacement of the top edges with respect to the lower merely illustrates the tendency there is to distortion between the parts when a belt is curved, as shown. If the top part were secured to the lower, buckling in the top would tend to take place, whereas my belt, permitting adjustment of the parts by sliding, does away 50 to a great extent with any such tendency to buckle.

Having two thicknesses instead of only one at the points at which bending takes place, or, in other words, having belt thick- 55

ness instead of belt thinness under the loading, I supply power of resistance to belt wear both from friction and from impact of blows of material. Again, by attaining this thickness by the use of two separate sheets of material instead of the use of a single sheet of their combined thickness I can make each of my sheets of a tougher and more firm and wear-resisting material than can be used for a single sheet of double thickness and still 70 can have a large percentage of flexibility in my favor.

As shown in Fig. 1, each section of the belt consists of three thicknesses or plies of canvas. *i* represents the stitches extending 75 through the three plies of canvas constituting the upper section, and *k* represents the stitches extending through the three plies of canvas constituting the lower section. The stitches *i* and *k*, extending through the central portion of the belt between the points *e* and *f*, may, if desired, be omitted, so that this portion of the belt will then differ no wise from a single thick belt.

In the modification shown in Fig. 2 I omit 90 the rivets *g* of Fig. 1 and rely entirely on the stitches *h* for securing the two sections of the belt together.

In the modification shown in Fig. 3 I omit 95 the stitches *h* of Fig. 1 and rely entirely on the rivets *g* for securing the two sections of the belt together.

As shown in all three figures, the edges of the upper section are thickened in order to provide 100 resistance should the belt run over sidewise and contact with the guide-rollers *b*. The drawings show the thickening of the edges effected by means of an extra ply or plies of canvas *l* inserted inside the outer plies of the belt.

My invention is not limited in its application to a belt of stitched canvas construction. It may be made of solid woven material, or of rubber, or of leather, or may be formed in any suitable way and of any suitable material; nor is my invention limited to the particular instrumentalities shown for securing the two sections together, as this may be done by glue, cement, or otherwise; nor if the belt be made of canvas or of other material put together in plies is the number of thicknesses or plies of material a material feature; nor is it necessary that the two sections of belt shall be of the same thickness, as for special reasons it may be desirable to make one part thicker or heavier than the other; nor is it essential to the embodiment of my broad invention that one of the sections should be thickened along its edges; nor is it necessary to the narrower embodiment of my invention that comprehends the thickening of the edges of one or both of the sections that this thickness should be secured by the particular expedient shown and described.

While I show a belt consisting of two sections or sheets, my invention would be equally embodied in a belt consisting of three or more sections or sheets.

5 I am aware that it has been proposed to apply a sheet of asbestos to the surface of the belt, as in the Ridgway patent, No. 632,750, of September 12, 1899. In the specification of that patent it is stated that the asbestos sheet may be riveted or otherwise attached to the belt, and in Figs. 3 and 4 of the drawings the sheet is apparently shown as riveted only between and not outside the lines of bend of the belt. This construction, 10 however, does not exhibit a belt embodying my invention, but at the most merely exhibits a belt not embodying my invention and a removable protecting-sheet correlated in a way somewhat analogous to the relation 15 existing between the two sections of my improved belt. Such a construction is not suggestive of my improved belt. Moreover, the belt and the asbestos sheet do not act in a manner similar to the two sections of my improved belt. In my improved belt the buckling of each section is but one-quarter of that which would occur if the two sections were secured to each other throughout their width. In the Ridgway construction the 20 buckling of the belt is no less than it would be if the asbestos sheet were secured to the belt throughout the latter's width, the reason for this being that the asbestos sheet being of a loose fibrous texture offers no substantial resistance to the displacement of its particles, and therefore if secured throughout its width to the belt would not subject the belt to any buckling strain substantially greater than that to which it would be subjected if the asbestos sheet were entirely absent.

Having now fully described my invention, what I claim, and desire to protect by Letters Patent, is—

1 A conveyer-belt comprising a plurality 45 of sheets secured together along their central portions and disconnected from, but contacting with, each other between their central portions and edges.

2 A conveyer-belt comprising three longitudinal portions, the central portion comprising a unitary or integral structure, while the two side portions consist of a plurality of disconnected but contacting sheets free to bend independently.

55 3. A conveyer-belt comprising a plurality of sheets secured together along their central portions only and free from each other outside their central portions.

4. A conveyer-belt comprising a longitudinal central portion composed of a plurality of sheets restrained from moving relatively both

longitudinally and laterally, and side portions each composed of a plurality of sheets restrained from relative longitudinal movement but capable of independent lateral movement.

5. A conveyer-belt comprising a plurality of superposed sheets contacting throughout their width and restrained from independent movement longitudinally but capable of limited movement laterally relatively to each other.

6. A conveyer-belt comprising a plurality of sheets secured together along their central portions only.

7. A conveyer-belt comprising a plurality of sheets contacting throughout but secured together along a part only of their width.

8. A conveyer-belt comprising a plurality of superposed sheets having contacting side portions adapted when bent to slide laterally one upon the other.

9. A conveyer-belt comprising a plurality of superposed sheets free and independent of each other only along the portions adjoining their longitudinal edges.

10. A conveyer-belt comprising a central longitudinal portion comprising a unitary or integral structure, and side portions consisting of a plurality of sheets free to bend independently, the edges of one or more of the sheets being thickened.

11. A conveyer-belt comprising a plurality of sheets secured together along their central portions and free from each other between their central portions and edges, the edges of the upper sheet being thickened.

12. A conveyer-belt comprising a plurality of sheets, and fastening means extending through all the sheets and securing them together along their longitudinal central portions only.

13. A conveyer-belt comprising a plurality of sheets and stitches securing the sections together along their longitudinal central portions only.

14. A stitched canvas belt comprising a plurality of sheets, each sheet composed of a plurality of thicknesses of canvas, stitches extending through the several thicknesses of each sheet across the entire width thereof, and fastening means securing together the several sheets along their longitudinal central portions only.

In testimony of which invention I have hereunto set my hand, at Philadelphia, on this 11th day of April, 1905.

GEORGE C. PLUMMER.
